US00D970992S

(12) **United States Design Patent** (10) **Patent No.:** **US D970,992 S**
(45) **Date of Patent:** **** Nov. 29, 2022**

(54) **PORTABLE RATCHET HAND TOOL**

(71) Applicant: **Hong Ann Tool Industries Co., Ltd.**,
Taichung (TW)

(72) Inventor: **Cheng-Wei Su**, Taichung (TW)

(73) Assignee: **Hong Ann Tool Industries Co., Ltd.**,
Taichung (TW)

(**) Term: **15 Years**

(21) Appl. No.: **29/755,861**

(22) Filed: **Oct. 23, 2020**

(51) LOC (13) Cl. **08-05**

(52) U.S. Cl.

USPC **D8/25**

(58) **Field of Classification Search**

USPC D8/14, 21, 24, 25, 26, 27, 29, 51, 59,

(57) **CLAIM**

The ornamental design for a portable ratchet hand tool, as shown and described.

DESCRIPTION

FIG. 1 is a perspective view of a portable ratchet hand tool showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is an exploded, perspective view of the hand tool of FIG. 1.

The broken lines depict portions of the portable ratchet hand tool that form no part of the claimed design.

The shaded surfaces and the solid lines represent the claimed portions of the design.

1 Claim, 8 Drawing Sheets
